UNITED STATES PATENT OFFICE.

WILLIAM A. BROWN, OF BROOKHAVEN, MISSISSIPPI.

ENVELOP AND STAMP MOISTENER.

No. 838,076.

Specification of Letters Patent.

Patented Dec. 11, 1906.

Application filed April 7, 1906. Serial No. 310,495.

To all whom it may concern.

Be it known that I, WILLIAM A. BROWN, a citizen of the United States of America, residing at Brookhaven, in the county of Lincoln and State of Mississippi, have invented new and useful Improvements in Envelop and Stamp Moisteners, of which the following is a specification.

This invention relates to improvements in envelop and stamp moisteners, the object of the invention being to provide a simple, convenient, and inexpensive device of this character in which effective provision is made for properly supporting a body of absorbent material within a bowl containing the moistening fluid and for securing an air-tight closure of the bowl to prevent to a maximum extent evaporation of such fluid.

In the accompanying drawings, Figure 1 is a perspective view of my improved envelop and stamp moistener with the cap or cover removed. Fig. 2 is a vertical section thereof with the cap or cover in position. Fig. 3 is a detail view of the holding-ring.

Referring to the drawings, the numeral 1 designates the body of the device, which may be made of glass or any other suitable material and of any desired form. This body is provided with a chamber 2, designed to be partially filled with a moistening fluid, such as water, the top of the body being formed with an opening 3, providing a contracted mouth or entrance to said chamber, the wall of the mouth having an upward extension in the form of an annular flange or rim 4.

A holding-ring 5 of channeled form receives and embraces the flange 4 and has its crown portion resting upon said flange and its sides 6 and 7 bearing, respectively, against the outer and inner faces of said flange. The lower edge of the outer side 6 of the ring rests upon the top wall of the body and is coextensive in depth with the flange, while the inner side 7 is of increased length to extend down into the mouth below the flange and to a point close to the bottom surface of the top wall. The ring may be fastened to the flange by cementing or otherwise securing it thereto, or made to grip the flange with sufficient force to retain it securely in position.

A body 8 of absorbent material, such as sponge, projects through and above and below the holding-ring and is held thereby in position. The depending portion of this absorbent body dips or is submerged in the

moistening fluid in the chamber 2, while the upper portion of the body projects above the ring and forms a surface on which the envelops or stamps may be readily moistened.

It will be observed that the ring holds the portion of the body passing therethrough in contracted condition, thus holding it from sagging against the greater weight of its depending portion, while the crown of said ring forms a rest-surface against which the top of the absorbent body may spread laterally without injury thereto upon the compression of the same under the pressure of the fingers in moistening an envelop or stamp.

A cap or cover 9 is provided to seal the mouth of the body and inclose and protect the upper portion of the absorbent material. This cap is formed with an annular bottom flange 10 to frictionally engage the outer side 6 of the holding-ring and effect a practically air and moisture tight joint. Above this flange 10 the body portion of the cap is outwardly swelled, as indicated at 11, to normally lie out of contact with the moistening portion of the absorbent material, whereby the fluid contained therein will be prevented from being deposited on the cap and draining therefrom onto the desk or table when the cap is removed. A knob or finger-piece 12 is provided upon the cap for convenience in manipulating the same.

It will be apparent that the invention provides a simple and inexpensive construction of moistening device, in which the body of moistening material is held securely in position and in which evaporation of the moistening fluid and the soiling of the absorbed material from the deposit of dirt and dust thereon will be effectually prevented by the air-tight connection of the cap with the holding-ring and that by the peculiar formation and construction of the ring and cap injury to or compression of the absorbent material in the use of the device and in the application and removal of the cap will be effectually obviated.

Having thus described the invention, what is claimed as new is—

1. A moistening device of the character described comprising a body having a contracted mouth provided with an upwardly-extending flange, a channeled holding-ring embracing said flange, a body of absorbent material held by the ring and projecting above and below the same, and a cap adapted

to inclose the upwardly-projecting portion of the absorbent material and frictionally engage the ring.

2. A moistening device of the character described comprising a chambered body having a contracted mouth provided with an upwardly-extending flange, a channeled holding-ring embracing said flange and having its crown portion resting thereon, said ring being provided with side flanges respectively engaging the outer face of the flange and projecting below the flange into the mouth, a body of absorbent material held by and pro-

jecting above and below said flange, and a closure-cap having an annular base-flange to engage the outer flange of the ring and having its body portion swelled to normally lie out of contact with the upwardly-projecting portion of the body of absorbent material.

In testimony whereof I affix my signature in presence of two witnesses.

WILLIAM A. BROWN.
